(57) **CLAIM**

The ornamental design for a glove with elastic support cuff as shown and described.

DESCRIPTION

FIG. 1 is a front perspective view of a glove with elastic support cuff in a first configuration;

FIG. 2 is a front elevation view thereof;

FIG. 3 is a front perspective view of a glove with elastic support cuff in a second configuration; and,

FIG. 4 is a front elevation view thereof.

The broken lines illustrate portions of the glove with elastic support cuff and form no part of the claimed design.

The interior of the glove forms no part of the claimed design.
